GEAR PUMP

John C. Walsh, Cedar Rapids, Iowa, assignor to Cherry-Burrell Corporation, Chicago, Ill., a corporation of Delaware

Filed Aug. 3, 1956, Ser. No. 601,863

12 Claims. (Cl. 103—7)

This invention relates to mix pumps used especially in the manufacture of ice cream to blend a gas into a liquid and pump the two fluids while they are being mixed.

One object of this invention is to provide a mix pump wherein fluids such as air and an ice cream mix liquid are metered, mixed and pumped by a unitary device.

Another object of the instant invention is to provide a mix pump housing which by the exchange of a few parts may have its output of ice cream mix doubled.

A further object of the present invention is to provide a mix pump which has a minimum of parts and seals so that it may be easily cleaned.

Another object of the invention herein disclosed is to provide a mix pump which may be dismantled easily in order to facilitate cleaning and therefore be acceptable to the dairy industry.

Still another object of the invention is to design a mix pump system with no interconnecting piping.

A further object of the invention is to provide a combination mix pump system in which the mix pump and the air pump operate at constant speed with respect to each other so as to control more accurately than heretofore the composition of the air and mix discharged therefrom.

A still further object of the invention is to reduce the number of moving parts required to pump, blend, and meter the air and mix handled by the pump.

Ice cream manufacturers are regulated as to the sanitation and quality of their products. It is important that the amount of air mixed in ice cream be controlled and that it is important to achieve a mechanism which is easily cleaned by one who is not necessarily a skilled mechanic. A mix pump which mixes air into an ice cream mix is required and this pump must be able to accurately measure the amount of air being mixed. Furthermore, the mixing machine must be simple so that a minimum of care is required and it must be easily dismantled for cleaning.

The means by which the foregoing and other objects are accomplished and the method of their accomplishment will readily be understood from the following specification upon reference to the accompanying drawings in which:

Fig. 1 shows a mix pump with several of its accessories as would be placed in an ice cream making machine;

Fig. 2 is a cross sectional view of a mix pump as taken on line 2—2 of Fig. 1;

Fig. 3 is a cross sectional view of a mix pump as taken on line 3—3 of Fig. 2;

Fig. 4 is a cross sectional view of a gear pump showing one of the gears in the pump as taken on line 4—4 of Figs. 1 and 3;

Fig. 5 is a perspective view of a filler block used in a mix pump on the mix liquid side;

Fig. 6 is a second, modification of the mix pump

2

shown with attachments used on ice cream making machines;

Fig. 7 is an end view of a mix pump taken on line 7—7 of Fig. 6;

Fig. 8 is a side view of the mix pump shown in Fig. 6 with the channel cover and air supply conduit removed;

Fig. 9 is a side view of a mix pump shown in Fig. 6 with the cover plate removed;

Fig. 10 is a cross sectional view of a mix pump taken on line 10—10 of Fig. 8; and

Fig. 11 is a cross sectional view of a mix pump taken on line 11—11 of Fig. 8.

Referring now to Fig. 1 in the drawings, mix pump 20 is connected to a liquid supply tank by a pipe 21. The liquid supply tank contains a mix liquid which is the basic ingredient for making ice cream. Connected to the opposite side of mix pump 20 is an air filter which provides air to the mix pump 20 through an air pipe 22. The flow of air to the mix pump is regulated by valve 23 which is interposed between the air filter and the mix pump. A discharge pipe 24 connects the mix pump with the freezer unit so that the aerated mixture is conducted from the mix pump to the freezer through pipe 24. A motor (not shown) drives a belt connected to a pulley which in turn drives the mix pump.

Pump 20 consists of a housing 25 as shown in Figs. 2 and 4 with a cover plate 26 attached thereto. Stud bolts 27 are screwed into drilled and tapped holes 29 of housing 25. Holes 31 in cover plate 26 register with the drilled and tapped holes 29 of housing 25 so that cover plate 26 may be placed immediately adjacent to housing 25 and studs 27 will protrude through the holes 31. Nuts 28 are screwed onto bolts 27 to hold the cover plate in place.

In the center portion of housing 25, Fig. 3, is a cylindrical center chamber 32 that has cover plate 26 forming one end thereof. Immediately adjacent to center chamber 32 and in communication therewith is a cylindrical air chamber 33 of a diameter and height equal to the first mentioned center chamber 32. A cylindrical mix liquid chamber 34 of a diameter and height equal to the center chamber 32 is immediately adjacent to said center chamber and opens into the center chamber on the side opposite the air chamber.

As shown in Fig. 2, the splined end 38 of drive shaft 35 is rotatably mounted in bushing 36 that is press fitted into housing 25. The opposite end 39 of drive shaft 35 is rotatably mounted in bushing 37 which is press fitted into a bore 41 in cover plate 26. The drive shaft 35 is so disposed that the longitudinal axis of the drive shaft coincides with the longitudinal axis of the aforementioned center chamber 32. Mounted on an enlarged portion 42 of drive shaft 35 is a drive spur gear 43 whose face width is approximately equal to the length of the center chamber. The outside diameter of gear 43 approximates the diameter of the center chamber 32 so that the top lands of teeth 44 may coact with the chamber walls 45 to form a fluid tight seal acting as a pumping and metering means.

A shaft 46 has its enlarged portion 48 press fitted into a hole 47 in housing 25 in such a manner that the longitudinal axis of shaft 46 coincides with that of air chamber 33. Mounted on the smaller portion 49 of shaft 46 is a bearing 51 and mounted on said bearing 51 is an air spur gear 52 of a face width equal to drive spur gear 43.

Spur gear 52 has an outside diameter that approximates the diameter of air chamber 33 so that the top lands of teeth 53 may coact with chamber walls 54 to form practically a fluid tight seal. Gear 52 is rotatably mounted on shaft 46 and teeth 53 mesh with teeth 44.

on gear 43 so that as gear 43 is rotated, gear 52 also rotates and pumps.

An enlarged portion 55 of shaft 56 is press fitted into hole 57 in housing 25. Shaft 56 has a smaller portion 58 which has a bushing 59 mounted thereon. A pumping means, gear 61, having half the face width of gear 43 is rotatably mounted on shaft 56 by means of bushing 59. The outside diameter of mix liquid spur gear 61 approximates the diameter of mix liquid chamber 34 so that the top lands of teeth 62 may coat with side walls 63 of mix liquid chamber 34.

Rigidly mounted on the smaller portion 58 of shaft 56 is a space filler block 64. The outside diameter of block 64 is approximately that of mix liquid chamber 34 so that block 64 may completely fill the volume not taken by the gear. Block 64 has a cut out portion 65 so that the block does not interfere with drive gear 43. In order to keep block 64 from turning due to the friction between the block and gear 61, the block has a pin hole 66 extending therethrough. Extending through a hole 68 in housing 25 is a pin 69 that extends into pin hole 66 of block 64.

Connecting mix liquid chamber 34 with a liquid pipe 21 is an inlet passage 71 which extends through housing 25. On the opposite side of the mix pump is an air inlet passage 72 in housing 25 which connects air chamber 33 with air pipe 22. A mixture discharge passage 73 extends from the junction of center chamber 32 and air chamber 33 to discharge pipe 24.

In operation, the power to the mix pump is supplied from a motor, not shown. The motor drives the belt which in turn drives a pulley attached to the splined portion 38 of drive shaft 35. Since gear 43 is fixed to drive shaft 35 at the enlarged portion 42, the gear 43 turns with drive shaft 35. In turn, both gears 52 and 61 turn with gear 43 since the teeth of each of the gears mesh with gear 43. As the gears are turning, an ice cream mix liquid is fed from the liquid supply tank to chamber 34 through pipe 21 and inlet 71. As the mix liquid reaches chamber 34, it is measured into the spaces 74 formed between teeth 62 and chamber wall 63. The rotation of the gear 61 carries the liquid to center gear 43. Since spur gear 61 has half the face width of spur gear 43, the liquid flows into the spaces 75 formed by teeth 44 and wall 45 of center chamber 32 instead of being squeezed out between the gears as in the operation of the usual gear pump. Because gear 61 has half the width of gear 43, the volume of chambers 75 is twice the volume of chamber 74 and therefore the mix liquid only half fills the chamber 75.

At the same time that the mix liquid is being drawn into chamber 34, the air spur gear 52 is turning and drawing air through the air filter along air pipe 52 through passage 72 and to chamber 33. The air fills up spaces 76 which are formed by teeth 53 and chamber wall 54 to act as a metering means. As the gear 52 rotates, the air is carried in spaces 76 to the point where gear 52 meshes with gear 42 and the air and mix liquid are intermingled. The meshing of the gears not only accomplishes the aeration of the mix but also the pumping of the aerated mix out discharge 73 to discharge pipe 24 and on to the freezer.

Since the spaces 74 have one half of the volume of spaces 76, the ratio of air to the liquid mix is two to one when the air is admitted at atmospheric pressure, and this results in an ice cream of a two hundred percent overrun. However, it is obvious that the amount of overrun may be reduced quite simply by adjusting the valve 23 so as to limit the amount of air admitted to the chamber 76. Also, by making the face of gear 61 narrower the amount of overrun could be increased. Since overrun in the ice cream industry is generally in the range of 85 to 100 percent, the valve 23 would normally be partially closed to a setting that would yield ice cream of the desired overrun. It will be understood, of course, that this invention affords a wide range of overrun con-

trol, depending on setting of the valve 23, all the way from approximately zero, with the valve 23 closed, to about 200, with the valve 23 open. It will be seen that with this construction the amount of overrun will always be the same because the spaces are held to a very close tolerance.

The above described mix pump lends itself to a simple modification which doubles the capacity of the pump at the same percentage of overrun. The modified mix pump of a high capacity is described below.

Referring to Fig. 6, a high capacity mix pump 100 has a pipe 101 connecting the mix pump 100 to a liquid supply tank and air inlet pipe 102 connecting an air filter to the mix pump. A valve 103 regulates the flow of air through pipe 102. A discharge pipe 104 connects the mix pump 100 with a freezer in which the mixture is frozen to make ice cream.

Mix pump 100 which is similar to the above described mix pump 20 consists of a housing 105 and a cover plate 106 attached thereto. As shown in Fig. 10 a housing 105 has holes 107 drilled and tapped therein and holes 108 are drilled in cover plate 106 in registry with holes 107. Stud bolts 109 are screwed into holes 107 and cover plate 106 is placed adjacent to housing 105 so that stud bolts 109 protrude through holes 108. Nuts 111 are then placed on stud bolts 109 to hold cover plate 106 in place.

Positioned in the central portion of housing 105, Fig. 9, is a cylindrical center chamber 112. Rotatably mounted in housing 105 is a drive shaft 113 which extends through the center portion of the chamber 112 and is also rotatably mounted in cover plate 106. Rigidly attached to drive shaft 113 is a spur gear 114 whose outside diameter is approximately equal to the diameter of center chamber 112 and the face width is equal to the length of the chamber. Teeth 115 of driven spur gear 114 have top lands which coat with walls 116 of chamber 112 to form a fluid seal.

Immediately adjacent and opening into chamber 112 is a cylindrical air chamber 118 of a length and diameter equal to said chamber 112. A shaft 117 is rigidly mounted in housing 105 so that the longitudinal axis of shaft 117 coincides with the longitudinal axis of air chamber 118. A bushing 119 is mounted on shaft 117 and a spur gear 121 is rotatably mounted on shaft 117 by means of said bushing 119. The width of gear 121 is equal to that of gear 114 and to the length of air chamber 118. Teeth 122 mesh with teeth 115 of drive spur gear 114. The outside diameter of air spur gear 121 is approximately the diameter of air chamber 118 so that the top lands of teeth 122 coat with side walls 123 of the air chamber to form a fluid seal. At the junction of air chamber 118 and center chamber 112 is an air junction 124. At the opposite side of the aforementioned junction of chambers 112 and 118 is a second junction 125 known as the discharge junction. Positioned immediately above junction 125 is an aerated mixture inlet hole 135.

Adjacent to center chamber 112 but on the opposite side of air chamber 118 is a mix liquid chamber 126, and at the junction of said chambers is an air and liquid mixture junction 134. The chamber 126 opens on to center chamber 112 and is of a diameter and length equal to the center chamber. An inlet passage 127 connects the chamber 126 and pipe 101. Rigidly connected to housing 105 and extending into chamber 126 is a shaft 128 whose longitudinal axis coincides with the longitudinal axis of chamber 126. Rotatably mounted on shaft 128 through bushing 129 is a gear 131. The width of gear 131 equals that of drive gear 114 and the teeth 132 mesh with teeth 115 of the drive gear 114. The top lands of teeth 132 coat with walls 133 of chamber 126 to form a fluid tight seal.

An air inlet orifice 136 in cover plate 106 is positioned in registry with air junction 124. Discharge passage 137

is provided in cover plate 106 in registry with junction 134 to permit the discharge of the aerated mixture from junction 134. A channel 139 connects discharge passage 137 with inlet passage 138. A cover plate 141 covers channel 139 and the plate 141 is attached to cover plate 106 by means of screws 142.

The coaction of discharge passage 137, channel 139 and inlet 138 provides a duct from junction 134 to passage 135 adjacent to junction 125.

In operation, power is supplied to mix pump 100 by a belt drive, connected with drive shaft 113 which rotates drive gear 114. Since the teeth of gears 114, 121, and 131 are interconnected in operation they all rotate at the same speed. Mix liquid is supplied to pumping and metering means in chamber 126 through inlet 127 and into the spaces 143 between teeth 132 and chamber wall 133.

At the same time that liquid is being fed to mix liquid chamber 126, air is supplied to air junction 124. As the gears rotate, the air flows into spaces 144 formed between teeth 122 and walls 123 and into the spaces 145 formed between teeth 115 and wall 116 so that the spaces 144 and 145 constitute metering means. As gear 114 rotates, the air spaces 145 move toward junction 134 and as gear 131 rotates, spaces 143 move toward junction 134. At junction 134, the air and liquid meet in equal volumes. The air and liquid are not only mixed at junction 134 but are also pumped out through hole 137 by the meshing of the teeth in gears 114 and 131. The constant meshing of teeth 115 and 132 pumps the mixture of an equal volume of air and equal volume of mix liquid through discharge passage 137 along channel 139 and then out through orifice 138.

As the mixture of an equal volume of air and mix liquid is discharged to passage 135 and then into discharge passage 146, the equal volume mixture meets with more air which comes up from junction 125. The air is pumped into the air liquid mixture and thus the additional air is blended into the mixture. The mixture with a greater content of air is then pumped through exhaust passage 146 and to discharge pipe 104 which takes the mixture to the freezer.

As may be seen, since gears 114, 121, and 131 are of equal size the teeth must be of equal size which therefore means that air spaces 143, 144, and 145 are also of equal size. The air space 143 fills with a given amount of liquid and space 145 fills with an equal amount of air. At junction 134 the equal amounts of air and liquid are mixed and pumped along the duct portion to the discharge passage 135. At the discharge passage and junction 125, one hundred percent more air is added to the mixture which results in an ice cream that has a two hundred percent overrun when the mixture is frozen in the freezer.

A further advantage should be noted that the basic housing used for the first described mix pump may be used for this second described mix pump. To convert from the lower capacity mix pump to the higher capacity mix pump the air line is simply removed and replaced by a plug, the cover plates are exchanged and the gear in the mix liquid chamber is replaced. Thereby the capacity of the mix pump is doubled.

While I have shown and described particular embodiments of my invention, it will occur to those skilled in the art that variations, changes, and modifications may be made without departing from my invention and I therefore aim in the appended claims to cover all such changes and modifications as fall within the true spirit and scope of my invention.

I claim:

1. In a device of the character described comprising a housing, a cover plate attached to said housing, a cylindrical center chamber in the central portion of said housing and the longitudinal axis of the center chamber and housing substantially perpendicular to each other and

one end of said chamber formed by the cover plate, a drive spur gear in said center chamber with the top lands of the teeth coating with the chamber walls in a fluid tight seal, a drive shaft attached to the drive spur gear on one end and the other end attached to a source of motive power, a cylindrical air chamber in said housing connecting to the center chamber and the diameter and height of said air chamber equal to that of the center chamber, an air spur gear in said air chamber with the top lands of the teeth coating with chamber walls in a fluid tight seal and meshing with the drive spur gear, a cylindrical mix chamber in said housing connecting to the center chamber, the diameter of said mix chamber equal to that of said center chamber, the height of said mix chamber equal one half that of the center chamber, a mix spur gear in said mix chamber and the top lands of the teeth coating with the walls of the chamber to form a fluid tight seal, a mix liquid passage opening into the mix chamber remote from the center chamber, an air inlet passage opening into the air chamber and a mix liquid air mixture discharge passageway opening to the junction of said air and center chambers.

2. A mix pump for blending mix liquid with air in the manufacture of ice cream comprising a housing, a cover plate, a cylindrical air chamber in said housing with the cover plate forming one end thereof, an air inlet passage opening into said air chamber, a shaft mounted on said housing and extending into said air chamber, an air spur gear mounted on said shaft and the top lands of the teeth coating with the chamber wall to form a fluid seal, a cylindrical center chamber in the housing opening into the air chamber, a drive shaft rotatably mounted in said housing extending into said center chamber, a drive spur gear attached to said drive shaft meshing with the air spur gear and the top lands of the teeth coating with the center chamber to form a fluid tight seal, a discharge passage extending from the junction of the air chamber and center chamber to the outer surface of the housing, a cylindrical mix liquid chamber in said housing opening into the center chamber having one half the height of said center chamber, a second shaft mounted in said housing and extending into the mix liquid chamber, a liquid spur gear rotatably mounted on said second shaft having an equal number of teeth to that on the drive spur gear and the top lands of the teeth coating with the mix liquid chamber wall to form a fluid tight seal, and a mix liquid inlet passage to said mix liquid chamber remote from said center chamber.

3. A mix pump for blending mix liquid with air in the manufacture of ice cream comprising a housing, a cover plate, fastening means attaching said cover plate to the housing, a center cylindrical chamber in said housing with the cover plate forming one end thereof, a shaft mounted in said housing and one end extending into said center chamber, a center spur gear mounted on said shaft, a cylindrical mix liquid chamber of equal diameter and height to the center chamber opening into said center chamber, a mix liquid inlet passage opening into the mix liquid chamber, a second shaft mounted in said housing extending into the mix liquid chamber, a mix liquid spur gear mounted on said second shaft and meshing with said center spur gear, a cylindrical air chamber opening into the center chamber and having a height and diameter equal to that of said center chamber, an air inlet passage opening into the junction of the air and center chambers, mix liquid air mixture discharge passage in said housing opening from the junction of the air and center chambers, a third shaft mounted in said housing and extending into the air chamber, an air spur gear mounted on said shaft, a mix liquid air mixture conduit from the junction of the mix liquid and center chambers to the discharge passage.

4. A device of the character described comprising a housing, a cover plate, fastening means holding the cover plate to the housing, a liquid air mixture inlet hole in

the cover plate, a liquid air mixture exit hole in the cover plate, a channel connecting the liquid air mixture inlet and exit holes, a channel cover plate attached to the cover plate covering the channel and holes entirely, a cylindrical mix liquid chamber in the housing with the cover plate forming one end thereof, a shaft mounted in said housing, a liquid gear of an outside diameter slightly smaller than the diameter of the liquid chamber and the width of the gear slightly less than the chamber height, a mix liquid inlet passage in the housing opening into the liquid chamber, a cylindrical center chamber of equal height and diameter to the liquid chamber and opening between said chambers, a drive shaft rotatably mounted in the housing extending through said center chamber, a drive gear of equal width and outside diameter to the liquid gear attached to said drive shaft in the center chamber, a junction between the center and liquid chambers, an air chamber of equal height and diameter to the liquid chamber opening into the center chamber, an air junction adjacent the opening between the air and center chambers, a discharge junction opposite the air junction and adjacent the opening between the air and center chambers, a discharge passage in the housing extending from said discharge junction, a second shaft mounted in the housing extending into the air chamber, and an air spur gear of a width and outside diameter equal to that of the drive gear rotatably mounted with relation to the housing mounted on the second shaft.

5. A gear pump comprising a housing having three substantially circular, intercommunicating chambers therein, two being end chambers communicating relatively diametrically with a center chamber, a gear in each of said chambers, the gears in the end chambers being meshed with the gear in the center chamber, a first fluid inlet port in said housing communicating with one of said end chambers remote from the center chamber, a second fluid inlet port in said housing communicating with the other of said end chambers, a single outlet port in said housing for said fluids, said outlet port communicating with the center chamber and the second fluid end chamber adjacent the meshing of the gears in said chambers, and means for transmitting the first fluid from its end chamber to said outlet port.

6. A pump as described comprising a housing, three substantially cylindrical chambers therein so positioned and intercommunicating that one serves as a center chamber and the other two are end chambers, a gear in each of said chambers, the center gear meshing with the two end gears, the top lands of the gear teeth co-acting with the chamber walls to act as a fluid seal, an inlet passage to one of the end chambers remote from the center chamber, an inlet passage to the other end chamber, a single discharge passage at the juncture of the center chamber and an end chamber, and means for communicating the other end chamber with said discharge passage.

7. A pump as described comprising a housing, three substantially cylindrical chambers therein so positioned and intercommunicating that one serves as a center chamber and the other two are end chambers, a gear in each of said chambers, the center gear meshing with the two end gears, the top lands of the gear teeth co-acting with the chamber walls to act as a fluid seal, an inlet passage to one of the end chambers remote from the center chamber, an inlet passage to the other end chamber, a single discharge passage at the juncture of the center chamber and an end chamber, and a passage in said housing for communicating the other end chamber with said discharge passage.

8. A fluid pump as described comprising a housing, three substantially cylindrical chambers therein so positioned and intercommunicating that one serves as a center chamber and other two are end chambers, a gear in each of said chambers having the top lands of the gear teeth

co-acting with the chamber walls to act as a fluid seal, the gear in the center chamber meshing with the gears in the end chambers, the gear in the center chamber and one of the end chambers being of substantially equal face width while the gear in the other chamber has a face width less than that of the other two gears, an inlet passage to one of the end chambers remote from the center chamber, an inlet passage to the other end chamber, and a single discharge passage at the juncture of the center chamber and the end chamber having the gear of equal face width whereby the fluid is transferred from the gear of lesser face width to the center gear and thereby to said discharge passage.

9. A pump as described comprising a housing, three substantially cylindrical chambers of equal height therein so positioned and intercommunicating that one serves as a center chamber and the other two are end chambers, a gear in each of said chambers, the gear in the center chamber meshing with the gears in the end chambers, the gear in the center chamber and one of said end chambers being of a face width equal to the height of their respective chambers, the gear in the other end chamber being of a face width less than the height of its respective chamber, a filler block in said last mentioned end chamber, said filler block being of a thickness equal to the height of the chamber less the face width of the gear in said chamber, the top lands of the teeth of said three gears co-acting with the respective chamber walls to act as a fluid seal, an inlet passage to each of the end chambers remote from the center chamber, and a single discharge passage at the juncture of the center chamber and the end chamber containing the gear of equal face width to that of the center chamber gear.

10. A gear pump comprising a housing having three substantially circular intercommunicating chambers therein, two being end chambers communicating relatively diametrically with the center chamber, a gear in each of said chambers, the top lands of the gear teeth co-acting with the respective chamber walls to act as a fluid seal, the gears in the end chambers being meshed with the gear in the center chamber, a first fluid inlet port in said housing communicating with one of said end chambers remote from the center chamber, a second fluid inlet port in said housing communicating with the other of said end chambers, a single outlet port in said housing for said fluids, said outlet port communicating with the center chamber and the second fluid end chamber adjacent the meshing of the gears in said chambers, and means for transmitting the first fluid from its end chamber to said outlet port.

11. The gear pump of claim 10 in which the means for transmitting the first fluid from its end chamber to said outlet port comprises a passageway formed in the housing from a point adjacent the meshing of the gears in the center chamber and the first fluid end chamber and a point in the outlet port.

12. The gear pump of claim 10 in which the means for transmitting the first fluid from its end chamber to said outlet port comprises the gear in the first fluid end chamber, said last named gear having a face width less than the face width of the gear in the center chamber.
